UNITED STATES PATENT OFFICE.

WILLIAM R. GORDON, OF ROCHESTER, NEW YORK, ASSIGNOR TO NORTH EAST ELECTRIC COMPANY, OF ROCHESTER, NEW YORK, A CORPORATION OF NEW YORK.

PNEUMATIC PRESS FOLLOWER.

Application filed April 18, 1922. Serial No. 554,964.

To all whom it may concern:

Be it known that I, WILLIAM R. GORDON, a citizen of the United States, residing at Rochester, in the county of Monroe and 5 State of New York, have invented certain new and useful Improvements in Pneumatic Press Followers; and I do hereby declare the following to be a full, clear, and exact description of the invention, such as 10 will enable others skilled in the art to which it appertains to make and use the same.

This invention relates to the follower used in a power-press for holding the blank frictionally in position during the operation 15 of the dies. Pneumatic pistons have been used in such devices for giving the necessary yielding pressure, and they have the advantage that the pressure may be substantially uniform throughout the stroke of the 20 press. Since the space, within a press of ordinary design, which is available for the mechanism of the follower is somewhat limited, it has been necessary to use pistons of 25 moderate diameter, and consequently to furnish air at high pressure in order to provide the requisite force.

The object of the present invention is to produce a pneumatic press-follower which 30 operates at high pressure, but in which this high pressure is produced by the action of 35 the follower itself, compressed air being supplied, if at all, from an outside source only at a relatively low pressure, such as that commonly used in the supply-systems 40 of factories.

To the foregoing end the invention consists in the mechanism hereinafter described, 45 as it is defined in the annexed claims.

The accompanying drawing is a diagrammatic sectional view, in elevation, of mechanism embodying the present invention.

Since the invention may be applied to a 50 press of any ordinary design, the construction of the press is not shown in the drawings, but the ram 1 is indicated as carrying a male die 2, which cooperates with a female die 3 resting on the bed 4 of the press. The head 5 of the follower works through 55 the middle of the die 3. The pneumatic mechanism comprises a cylinder 6 fixed below the bed and divided by a diaphragm 7. Two pistons 8 and 9 work in the upper and lower parts of the cylinder, and the upper piston 8 supports the head 5. The 55 pistons are connected by a rod 10 which

is perforated to provide a passage 11 by which the pressure below the two pistons is equalized. This tandem arrangement of pistons is used to secure the necessary force with pistons of small diameter, and is not a 60 novel or essential feature of the present invention.

The air used in the follower-mechanism is derived, in the first instance, from any 65 convenient source of supply, such as a pipe 12, which may be a part of the system common in factories. From this pipe it is admitted, through a pipe 13 and a check-valve 14, to the bottom of the cylinder 6. A pipe 15 also communicating (through the pipe 70 13) with the bottom of the cylinder, permits air to escape, through a check-valve 16, to a tank 17. The valve 16 is provided with means by which it may be forcibly lifted 75 from its seat at each up-stroke of the press, these means being shown diagrammatically as comprising a valve-stem or rod 18 carrying a nut at its upper end, and an arm 19, projecting from the ram 1, the end of the arm being perforated to receive the rod 18, 80 which slides freely in the perforation. The nut 20 is adjusted to be engaged and slightly lifted at the upper extremity of the up-stroke of the ram.

The tank 17 should be large in proportion 85 to the capacity of the cylinder 9, and it is provided with an outlet through a relief-valve 21, this valve being adjusted for the pressure which is to be maintained in the tank. To economize in power, the outlet is 90 preferably arranged to discharge into the supply-pipe 12.

Assuming that the pressure maintained 95 in the supply-pipe 12 is 40 lbs., and that the relief-valve 21 is adjusted for 80 lbs., the operation of the apparatus is as follows: At the outset the entire pneumatic system will be filled with air, from the supply 12, at 40 lbs., and the follower will be raised to its upper limit, as shown. The press is then 100 permitted to make a few idle strokes, and at each down-stroke the air in the cylinder, originally at 40 lbs. pressure, is further compressed and expelled, through the check-valve 16, into the tank 17. At each up-stroke air enters through the pipe 13 and the valve 14 to refill the cylinder.

As soon as the pressure of 80 lbs. has been 105 reached in the tank the follower is ready for regular operation. The follower is raised, 110

as before, by air entering the cylinder at 40 lbs., but at the end of the up-stroke the valve 16 is momentarily lifted, thus permitting air to return from the tank to the cylinder, sufficient to raise the pressure in the cylinder from 40 lbs. to 80 lbs. The pressure of 80 lbs. is maintained substantially constant throughout the down-stroke of the follower, since any surplus escapes 10 through the valve 16 into the tank and from the tank through the escape-valve 21.

It will be apparent that at each operation of the press air at 40 lbs. pressure is admitted in volume just sufficient to fill the cylinder, and that this additional quantity of air is then compressed into the tank, so that provision is made for whatever leakage is unavoidable in the system, the surplus being discharged back into the supply-pipe 15. 12. The follower thus acts as a pump to maintain the air at the pressure necessary for its operation, and the only need for the initial compression of the air in the supply 20. 12 is to raise the follower and thus dispense with the use of springs or mechanism for 25 this purpose.

The invention is not limited to the embodiment thereof hereinbefore described; but it may be embodied in various other forms within the scope of the following 30 claims.

The invention claimed is:

1. In a press-follower, the combination of a cylinder; a piston therein; means for admitting air to the cylinder for raising the piston; a pressure-tank; connections between the tank and the cylinder; and means 35

in said connections for preventing flow of air from the tank to the cylinder during the up-stroke of the piston, said means 40 operating to permit such flow after the completion of the up-stroke.

2. In a press-follower, the combination of a cylinder; a piston therein; means for admitting air at relatively low pressure to 45 raise the piston and fill the cylinder; a tank for air at relatively high pressure; connections between the tank and the cylinder; and means controlling said connections and operating automatically to permit air to 50 escape from the cylinder to the tank during the down-stroke of the piston, but to prevent the return of air from the tank to the cylinder except just at or preceding the beginning of the down-stroke of the piston. 55

3. In a press-follower, the combination of a cylinder; a piston therein; a source of supply of air at relatively low pressure; a passage from said source to the cylinder, controlled by a non-return valve; a tank 60 for air at relatively high pressure; an automatic escape-valve for controlling the pressure in the tank; a passage from the escape-valve to said source of supply; a passage from the cylinder to the tank; and valve- 65 means controlling the last-mentioned passage and adapted to permit air to flow freely from the cylinder to the tank, to permit air to return to the cylinder from the tank after the substantial completion of the up-stroke of the piston, and to prevent the return of air from the tank during the up-stroke of the piston. 70

WILLIAM R. GORDON.
